PRESS OPERATING MECHANISM

Clifton S. Malott, Jr., Norwood, Ohio, assignor to
The American Laundry Machinery Company,
Norwood, Ohio, a corporation of Ohio

Application January 11, 1935, Serial No. 1,326

4 Claims. (Cl. 192—133)

This invention relates to a pressing machine and more especially to improved control mechanism therefor.

My improved pressing machine includes a guard movable into and out of position between the pressing members and an operator, to guard the latter against injury. The control mechanism for this guard comprises a motor which upon completion of movement of the guard to protecting position causes the action of the press closing means thus insuring that the guard will always be in protecting position when the pressing members are moved into final engagement.

Another feature of my invention is the provision of a cylinder and piston motor for moving the guard to protecting position, power means for closing the press, and means operable upon a predetermined travel of the guard moving piston for actuating the press closing power means.

My improved control mechanism provides a cylinder and piston motor for moving a guard to guarding position with a port in the cylinder wall adapted to be uncovered by the piston when it has moved the guard to guarding position and this port communicates with a fluid actuated power means for closing the press. My invention therefore provides a structure which insures that the guard is in guarding position before the press closing means acts.

Other objects and advantages of my invention include a single control valve which remains in supply or exhaust position upon movement thereto by the operator. This construction provides a very simple press to operate.

In the drawing I have illustrated a form of mechanism devised to carry out the above objects and purposes which will be clearly understood from the attached specification and the essential features will be summarized in the 40 claims.

In the drawing, Fig. 1 is an end elevation of a pressing machine embodying my invention with the parts in open position and with portions thereof in section to more clearly illustrate the 45 operation; Fig. 2 is a view similar to Fig. 1 with the guard in closed position; while Fig. 3 is a sectional view along the line 3—3 of Fig. 2.

I have illustrated my invention as applied to a pressing machine having a frame 10 upon 50 which is mounted in fixed position a pressing bed 11. Upon a portion of the frame is pivotally mounted a head lever 12 which carries at its free end a pressing head 13 which is adapted to coact with the bed member 11. For moving 55 the head into and out of pressing engagement I

provide a toggle mechanism 14 connected between the head lever and the frame and having an operative connection with a motor 15 which comprises a cylinder 16 in which reciprocates a piston 17. A spring 18 connected between the toggles and the frame biases the toggles to broken position, thus maintaining the head in its raised or open position.

For protecting the operator against injury as the pressing members close, I have provided a 10 guard 19 adapted to be moved into and out of protecting position between the operator and the pressing members. This guard as shown comprises a frame 20 supporting a protecting grille 21 but it will be understood that my invention is applicable to any suitable guard. For moving the guard I have provided a bell-crank 22 pivotally mounted on the frame and in the present instance having the same pivot as the head lever. The short arm 23 of the bell-crank is connected with the guard and the longer arm 24 of the bellcrank extends downwardly and has an operating connection with a power motor 25. This motor comprises a cylinder 26 in which reciprocates a piston 27 whose 25 piston rod 28 has a pivot and slot connection 29 with the arm 24 of the bellcrank. A spring 30 between the bellcrank and the frame biases the guard to its raised or open position.

Means is provided to insure that the guard 30 operating motor 25 will complete its stroke to move the guard into protecting position before the press closing motor 15 is actuated to close the press. In the present instance I have provided a port 31 in the wall of cylinder 26 which 35 communicates by an open passageway 32 with the working face of piston 17. The port 31 is so positioned as to communicate with the working portion of cylinder 26 when piston 27 has completed its power stroke so that when the 40 parts reach the position of Fig. 2 working fluid from cylinder 26 will pass out of port 31 so that fluid passing through the passageway 32 is available to actuate the press closing means. A second port 33 in the wall of cylinder 26 communicates with the atmosphere and is positioned so as to lie beyond the working face of piston 27 when it has completed its power stroke and the 45 parts reach the position of Fig. 2. It results from this construction that with the parts in the open position of Fig. 1, cylinder 16 is in communication with the atmosphere through passageway 32, port 31, cylinder 26 and port 33, whereas when the piston 27 has completed its power stroke and moved the guard into pro- 55

tecting position, as shown in Fig. 2, piston 21 has closed the exhaust port 33 and opened port 31 so that motive fluid may pass out of cylinder 26 into cylinder 16 to operate piston 17.

5 The supply of motive fluid to the power mechanism is by way of a combined flow and exhaust conduit 34 in communication between cylinder 26 and valve casing 35. While I have illustrated one form of valve suitable for my purpose, it will be understood that any form of valve is suitable which remains in its supply or exhaust position upon movement thereto by the operator. In the valve casing 35 I have illustrated a movable member 36 having a passageway 37 therein for establishing communication between conduit 34 and the exhaust outlet 38 when the valve parts are in the position of Fig. 1. The member 36 is so constructed that it closes the outlet 38 and establishes communication between conduit 34 and a source of motive fluid 39 when the valve parts are in the position of Fig. 2. For moving the valve member 37 I have provided the latter with a stem 40 having a connection with a manual 41.

10 In the operation of the pressing machine described and with the parts in the position of Fig. 1, the operator arranges the work upon the bed 11 and moves the manual 41 from the position of Fig. 1 to the position of Fig. 2. Motive fluid then travels through conduit 39, casing 35 and conduit 34 to cylinder 26 against the working face of piston 27 causing a power stroke of the latter. When the guard reaches protecting position, piston 27 is in the position of Fig. 2 and motive fluid flows from cylinder 26 through passageway 32 to the working face of piston 17 in cylinder 16. Piston 17 then makes a power stroke which straightens the toggles and moves the pressing members into pressing engagement.

15 The parts will remain in this position until the operator returns manual 41 to the position of Fig. 1. This will exhaust fluid from motor 17 through passage 32, cylinder 26, conduit 34, casing 35 and outlet 38 thus permitting spring 18 to open the press. As soon as piston 27 moves to the right of port 31, cylinder 16 completes its evacuation through the port 33, while cylinder 26 continues to evacuate through conduit 34 and outlet 38 while spring 30 returns the guard to its open position.

I have illustrated motors 15 and 25 as combined in a common structure but it will be understood that this is mainly for convenience and that these units may be separated if desired.

20 55 What I claim is:

1. In a pressing machine, a pair of coacting

relatively movable pressing members, fluid actuated power means for relatively moving said members to close the press, a guard movable into and out of position for protecting an operator against injury, a cylinder and piston motor for moving said guard to protecting position, a port in said cylinder uncovered by said piston when said guard is in protecting position, and a passageway leading from said port to said power means.

2. In a pressing machine, a pair of coacting relatively movable pressing members, a guard movable into and out of position for protecting an operator against injury, a cylinder and piston motor for moving said guard to protecting position, an open port in said cylinder uncovered by said piston when said guard is in protecting position, and means actuated by fluid escaping from said port for relatively moving said pressing members to close the press.

25 3. In a pressing machine, a pair of coacting relatively movable pressing members, means for moving one of said members to close the press including fluid actuated power means, a guard movable into and out of position for protecting an operator against injury, a cylinder and piston motor having an operative connection for moving said guard to protecting position, inlet and outlet ports communicating with said power means for controlling the flow and exhaust of motive fluid thereto, and said ports being arranged so that said piston closes said outlet port and opens said inlet port when said motor has moved said guard to protecting position.

30 4. In a pressing machine, a pair of coacting relatively movable pressing members, means including a cylinder and piston motor for relatively moving said members to close the press, a guard movable into and out of guarding position between said pressing members and an operator, means for moving said guard including a cylinder and piston motor having a power stroke adapted to move said guard to guarding position, a port in the cylinder wall of said guard moving motor adapted to communicate with the motive fluid in the said motor when it has completed its power stroke, an open passageway leading from said port to the working face of said press-closing motor, a second port in the cylinder wall of said guard moving motor lying beyond the working face of the piston of said guard moving motor when it has completed its power stroke, said second port communicating with the atmosphere, and a fluid supply conduit communicating with said guard moving motor.
